UNITED STATES PATENT OFFICE

RICHARD C. ENDERWOOD, OF NEWARK, NEW JERSEY, ASSIGNOR TO BRANDES LABORATORIES, INCORPORATED, OF NEWARK, NEW JERSEY, A CORPORATION OF NEW JERSEY

DESIGN FOR AN ESCUTCHEON FOR CONTROL DIALS

Application filed April 23, 1929. Serial No. 30,986. Term of patent 3½ years.

To all whom it may concern:

Be it known that I, RICHARD C. ENDERWOOD, a citizen of the United States, residing at Newark, in the county of Essex and State of New Jersey, have invented a new, original, and ornamental Design for an Escutcheon for Control Dials, of which the following is a specification, reference being had to the accompanying drawings, forming part thereof.

Fig. 1 is a plan view of an escutcheon for control dials, showing my new design.

Fig. 2 is a side elevational view of the escutcheon plate shown in Fig. 1.

I claim:

The ornamental design for an escutcheon for control dials, as shown.

In witness whereof, I hereunto subscribe my name this 18th day of April, A. D. 1929.

RICHARD C. ENDERWOOD.
